CLAIM

The ornamental design for a holder ring for cardiotomy reservoir, substantially as shown and described.

DESCRIPTION

FIG. 1 is a perspective view of a holder ring for cardiotomy reservoir showing our new design;

FIG. 2 is a top plan view thereof;

FIG. 3 is a front elevational view thereof;

FIG. 4 is a rear elevational view thereof;

FIG. 5 is a left side elevational view thereof;

FIG. 6 is a right side elevational view thereof; and

FIG. 7 is a bottom plan view thereof.

FIG. 1

FIG. 2

FIG. 3

FIG. 4

FIG. 5
